CAP-FEEDING MECHANISM FOR RIVETING-MACHINES.

1,176,911.

Specification of Letters Patent.

Patented Mar. 28, 1916.

Application filed November 10, 1915. Serial No. 60,689.

To all whom it may concern:

Be it known that I, ALFRED L. LILLEY, a citizen of the United States, residing at Hartford, in the county of Hartford and State of Connecticut, have invented a new and useful Improvement in Cap-Feeding Mechanism for Riveting-Machines, of which the following is a specification.

This invention relates to a mechanism which is particularly designed for feeding hollow caps to tubular rivets in a machine which is especially adapted for fastening together parts of harness and other heavy leather goods.

15 The object of the invention is to provide for feeding rounded hollow caps into position to receive the ends of the rivets, a mechanism adjustable for rivets of different lengths which is inexpensive to build, easy 20 to apply to riveting machines as at present built, reliable in action and durable in use.

Figure 1 of the accompanying drawings shows a side elevation of a well known tubular riveting machine provided with a 25 hollow cap feeding mechanism which embodies this invention. Fig. 2 shows on larger scale a front elevation, with parts in section, of the vertically movable anvil, the cap guide, and the mechanism for transferring the caps one at a time from the end of the feed trough into the cap guide above the upper end of the anvil. Fig. 3 shows a 30 plan of the cap guide and its support, and the slide and the means which locks the slide and prevents the machine from being operated if there is no cap in position to be passed into the cap guide above the anvil. Fig. 4 is a front view, with parts in section, illustrating the manner of locking 35 the anvil in its raised position, that is, in the position it occupies when the cap and rivet are being put together. Fig. 5 is a similar view illustrating the position of the parts when the anvil is being unlocked so 40 that it may descend into position to receive another cap. Fig. 6 is a detail view of the front end of the operating treadle. Fig. 7 is a sectional view of the cap-hopper, the belt which picks the caps from the hopper 45 and delivers them to the feed trough, and the plates for agitating the caps in the hopper. Fig. 8 is a section showing the method of jointing the lever which raises and lowers the anvil so that it will slip and not 50 cause damage to the parts in case an obstruction interferes with their free work-

ing. Fig. 9 shows a rivet and cap before they are assembled. Fig. 10 shows a rivet and cap after they are assembled.

The headed rivets 1 are deposited promiscuously in the hopper 2 and by common mechanism are selected and allowed to feed through the trough 3 down to the delivery mouth 4. The rivets are forced down from the delivery mouth by the punch 5 which is connected with a lever 6 that is pivoted to the top of the frame and is reciprocated by the crank rod 7. This part of the machine is old and in common use, and as the parts are well known they are not herein shown and described in detail.

The caps 8, which are cup-shaped, sheet metal articles, circular in outline with rounded edges and openings into them from one side only, are thrown promiscuously into the hopper 9. From this hopper those which have their openings downward are picked by the pins 10 on the belt 11 and carried into the feed trough 12. The feed belt passes around wheels 13, the axle of one 50 of which has a pulley 14 driven by a belt 15 from a pulley 16 on a shaft having a pulley 17 that is driven by a belt 18 from a pulley 19 on the drive shaft 20. Connecting up the parts in this manner causes the feed belt to 55 move slowly, but with sufficient speed to keep the feed trough filled with caps. Plates 21 are arranged to project into the bottom of the hopper to agitate the caps so that they will be more readily picked up by the pins 90 on the feed belt. These plates are lifted by a rod 22 that is pivoted to the frame and extends rearwardly so as to be engaged by an ear 23 clamped on the crank rod. A pin 24 which connects and guides the lower ends 95 of the plates is engaged by the rod so that the plates are lifted each time the punch is forced down by the crank mechanism. The feed trough receives the caps with the openings down and it is curved around so that 100 at its discharge end the caps lie with their open sides up.

The discharge end of the feed trough opens into a channel 25 in which moves a slide 26. When the slide is drawn out its 105 front end is back of the opening from the discharge end of the feed trough. When the slide is moved in its front end pushes a cap along the channel from the discharge end of the feed trough through the opening 110 27 into the cap guide 28 above the upper end of the anvil 29. The slide is engaged

by the forked upper end of an arm 30 on an arbor 31 attached to which is a lever 32. The end of this lever is by the rod 33 connected with the foot pad 34 of the operating treadle 35. A spring 36 normally holds the rod up and the slide drawn out. The foot pad is hinged to the treadle so that it has a slight movement independent thereof. When the foot pad is first depressed the slide 10 is pushed in so as to carry a cap to the cap guide. Further downward movement of the foot pad then depresses the treadle and through the rod 37 operates the common clutch mechanism (not shown) always provided in such machines, in the usual manner for setting the machine in operation. A pawl 38 is held by a spring 39 with one end projected into a slot 40 in the transfer slide. The other end of the pawl is engaged by a 20 pivoted finger 41, the front end of which projects into the cap channel in front of the discharge end of the feed trough. If there is a cap in the slide channel, as shown in Fig. 3, when the slide moves forward this cap 25 engages the finger and oscillates it so that the pawl is turned out of the slot, allowing the slide to move inward. If there is no cap in the channel the end of the pawl obstructs the movement of the slide, and when the 30 slide cannot move in, the treadle cannot be depressed and the clutch thrown in for setting the machine in operation; that is, by means of this mechanism if there is no cap in position to be fed into the cap guide above 35 the anvil, the machine cannot be operated.

The cap guide 28 is a long tube with its exterior threaded and turned into the end of the lower part of the frame 42 so that it may be adjusted up and down according to the 40 lengths of the rivets. The cap opening 27 into the guide is some distance below the upper end. This enables a piece of work with downwardly projecting sides to be placed over the cap guide and beneath the 45 punch so that the parts of the work can be fastened by a rivet and cap. If the cap opening was at the top of the cap guide and the feed trough came to it the trough and other mechanisms would interfere with such 50 pieces of work which are common, particularly in the manufacture of harness parts.

The anvil is a long round rod 29 with its lower end adjustably set into a block 44 that is movable up and down between supporting 55 and guiding plates 45, which at the bottom are fastened to the base 43 and at the top to the frame 42. The anvil block is connected with a block 46 that is also movable up and down the guide plates. This connection between the blocks is yielding and is made by the screw 47 and spring 48, which thrusts between the head of the screw and the plate 49 which is secured to the lower 60 end of the block 44. The anvil blocks are 65 raised and lowered by the engagement of

the forked front end of the lever 50 with a stud 51 that is set into the block 46. The rear end of this lever is frictionally clamped by the screw 52 on the hub 53 of the lever 54, which on its rear end has a roll 55 traveling in the cam slot 56. As a result of the frictional joint between these levers, if the anvil or the blocks should become obstructed, the connection will slip so that the mechanisms will not be injured. Secured to the 70 block 46, and traveling up and down therewith, are spring arms 57. When the anvil blocks reach the upper limit of their movement these spring arms engage pins 58 mounted in the guide plates, and force them 80 into sockets 59 in the block 44, and thus lock that block with the anvil raised. After the cap and rivet have been set together by the blow of the punch the anvil blocks are moved downward. During the first part of 85 the movement the lower block 46 moves down a short distance, the spring 48 allowing this. After the block 46 has been lowered sufficiently to carry the spring arms away from the locking pins the pins are 90 drawn out by the springs 60 that are fastened to the guide plates, and then the block 44 and anvil can move down full distance.

By means of the mechanism described, which can be attached to machines in common use without change in any of the present mechanism, except the cap guide, the hollow caps are positively and surely fed above the anvil in such a position that large irregular pieces of work can be placed between the anvil and punch and riveted. These caps thus placed are carried up positively in an accurate guide to the lower ends of the rivets, and before the parts come together the anvil is positively locked so that 100 powerful blows can be struck on the rivets for causing their ends to expand into the caps. The anvil is not only positively locked when receiving the blow, but it is surely released, and should its movement be 105 obstructed none of the parts will be damaged. Furthermore, the machine cannot be operated if there is no cap to be fed and carried up to the lower end of the rivet. The anvil is easily adjusted for rivets of varying 110 length by turning it more or less into the anvil block. The cap guide can be raised or lowered by screwing it up or down, and the transverse feed mechanism can also be raised 115 or lowered.

The invention claimed is;

1. The combination with a machine having a reciprocating rivet punch, of mechanism for feeding and supporting caps beneath the punch comprising a hopper, means for removing caps from the hopper, a feed trough for conducting caps from the hopper, a cap guide for receiving the caps, mechanism for transferring the caps one at a time from the feed trough into the cap 130

guide, an anvil movable up and down in the cap guide for lifting the caps from entrance position to setting position, mechanism for reciprocating the anvil, and mechanism for locking the anvil so that it will rigidly support a cap against downward movement when the rivet is driven into it by the rivet punch.

2. The combination with a machine having a reciprocating rivet punch, of mechanism for feeding and supporting caps beneath the punch comprising a hopper, means for removing caps from the hopper, a feed trough for conducting caps from the hopper, a channel for receiving caps at the lower end of the feed trough, a cap guide for receiving the caps, mechanism for pushing the caps from the channel into the cap guide, an anvil movable up and down in the cap guide for lifting the caps from entrance position to setting position, and mechanism for locking the anvil and causing it to resist the blow when the rivets are driven down into the caps by the rivet punch.

3. A mechanism for feeding caps comprising a hopper, means for withdrawing caps from the hopper, a feed trough leading from the hopper, a cap guide, mechanism for transferring caps one at a time from the feed trough to the cap guide, an anvil movable up and down in the cap guide, mechanism for raising and lowering the anvil, pins for locking the anvil in its raised position, and means for moving the pins into and out of locking position.

4. A mechanism for feeding caps comprising a hopper, means for withdrawing caps from the hopper, a feed trough leading from the hopper, a cap guide, mechanism for transferring caps one at a time from the feed trough to the cap guide, an anvil movable up and down in the cap guide, an anvil block to which the anvil is adjustably connected, mechanism for raising and lowering the block, and means for locking the block in its upper position while a cap is being set on a rivet.

5. A mechanism for feeding caps comprising a hopper, means for withdrawing caps from the hopper, a feed trough leading from the hopper, a cap guide, mechanism for transferring caps one at a time from the feed trough to the cap guide, an anvil movable up and down in the cap guide, an anvil block carrying the anvil, mechanism for raising and lowering the block, pins for locking the block in its upper position, means connected with the block for moving the pins into locking position, and means for releasing the block.

6. A cap feeding attachment for a riveting machine comprising a cap feeding mechanism, a cap guide, mechanism for transferring caps from the feeding mechanism to the guide, an operating treadle, connections be-

tween the treadle and the transfer mechanism, an anvil movable in the cap guide, mechanism for raising and lowering the anvil, and mechanism for temporarily locking the anvil in its raised position.

7. A cap feeding attachment for a riveting machine comprising mechanism for feeding caps, a cap guide, an anvil movable up and down in the cap guide, mechanism for raising and lowering the anvil, mechanism independent of said raising and lowering mechanism for temporarily locking the anvil in its upper position, mechanism for transferring caps to the cap guide above the anvil in its upper position, mechanism 70 the transfer mechanism.

8. A cap feeding attachment for a riveting machine comprising mechanism for feeding caps, a cap guide, an anvil movable up and down in the cap guide, mechanism 75 for raising and lowering the anvil, mechanism for locking the anvil in its upper position, mechanism for transferring caps to the cap guide above the anvil, an operating treadle, and a connection from the operating 80 treadle to the transfer mechanism for reciprocating said mechanism.

9. A cap feeding attachment for a riveting machine comprising mechanism for feeding caps, a cap guide, an anvil movable up and down in the cap guide, mechanism 95 for raising and lowering the anvil, mechanism for locking the anvil in its upper position, and means carried by the anvil for causing said locking mechanism to 100 lock the anvil in its upper position.

10. A cap feeding attachment for a riveting machine comprising feeding mechanism, a cap guide, an anvil movable up and down in the cap guide, mechanism for raising and 105 lowering the anvil, and mechanism engaged by the upward movement of the anvil for locking the anvil in its upper position.

11. A cap feeding attachment for a riveting machine comprising mechanism for 110 feeding caps, a cap guide, an anvil movable up and down in the cap guide, mechanism for raising and lowering the anvil, mechanism for locking the anvil in its raised position, mechanism for transferring 115 caps from the feeding mechanism into the cap guide above the anvil, an operating treadle, a connection between the operating treadle and the transfer mechanism, and mechanism for preventing the movement of 120 the operating treadle in case there is no cap to be transferred into the cap guide.

12. A cap feeding attachment for a riveting machine comprising mechanism for feeding caps, a cap guide, an anvil movable 125 up and down in the cap guide, mechanism for raising and lowering the anvil, mechanism for locking the anvil in its raised position, mechanism for transferring caps from the feeding mechanism into the cap 130

guide above the anvil, an operating treadle, a connection between the operating treadle and the transfer mechanism, and mechanism for obstructing the movement of the transfer mechanism when there is no cap in front of it to be transferred into the cap guide.

13. An attachment for a riveting machine comprising a cap feeding mechanism, a cap 10 guide, an anvil movable up and down in the cap guide, an anvil block, mechanism for raising and lowering the anvil block, and mechanism independent of said raising and lowering mechanism for temporarily locking the anvil block in its upper 15 position.

14. An attachment for a riveting machine comprising a cap feeding mechanism, a cap 20 guide, an anvil movable up and down in the cap guide, an anvil block, mechanism for raising and lowering the block, and mechanism actuated by the upward movement of the block for locking the block in its upper position, said mechanism being released by 25 the downward movement of the block for unlocking the same.

15. An attachment for a riveting machine comprising a cap feeding mechanism, a cap 30 guide, an anvil movable up and down in the cap guide, a sectional anvil block, mechanism for raising and lowering the anvil block, and mechanism actuated by the upward movement of the anvil block locking 35 said block in its upper position.

16. An attachment for a riveting machine comprising a cap feeding mechanism, a cap 40 guide, an anvil movable up and down in the cap guide, a sectional anvil block, mechanism for raising and lowering the anvil block, and means carried by the lower section of the anvil block for engaging the locking mechanism on its upward movement and releasing the locking mechanism on its downward movement.

17. An attachment for a riveting machine comprising a cap feeding mechanism, a cap 45 guide, an anvil movable up and down in the cap guide, a block to which the anvil is connected, a block yieldingly attached to the anvil block, mechanism for raising and lowering said blocks, means adapted to engage the anvil block and lock it in its upper position, means carried by the yielding block 50 and adapted to engage the locking means and cause them to lock the anvil block in its upper position, and means for withdrawing the locks and releasing the anvil block when the yielding block is moved downward.

18. An attachment for a riveting machine having an adjustable cap guide, an adjustable anvil movable up and down in the cap 55 guide, a block carrying said anvil, a block yieldingly connected to the anvil block, mechanism for raising and lowering said blocks, pins adapted to engage and lock the anvil block in its upper position, and springs carried by the yielding block and adapted to engage the locking pins when the blocks move up and to release the locking pins when the blocks move down.

ALFRED L. LILLEY.
